UNITED STATES PATENT OFFICE.

MARGARET H. MAUZY, OF SAN FRANCISCO, CALIFORNIA.

DESIGN FOR A DOLL.

52,803.

Specification for Design.

Patented Dec. 24, 1918.

Application filed September 12, 1918. Serial No. 253,835. Term of patent 3½ years.

To all whom it may concern:

Be it known that I, MARGARET H. MAUZY, a citizen of the United States, and a resident of the city and county of San Francisco, State of California, have invented a new, original, and ornamental Design for a Doll, of which the following is a specification, reference being had to the accompanying drawings, forming part thereof.

Fig. 2 is a side view of the doll.

Fig. 3 is a rear view of the doll.

I claim:

The ornamental design for a doll substantially as shown.

MARGARET H. MAUZY.

Witnesses:

HENRY E. MORROW,
P. NOVAK.
